CAP FEEDING APPARATUS

Robert J. Stewart and John S. Bartley, Baltimore,
Md., assignors to Crown Cork & Seal Company,
Inc., Baltimore, Md., a corporation of New York

Application August 29, 1941, Serial No. 408,875

1 Claim. (Cl. 226—88.1)

This invention relates to cap feeding means and has as a principal purpose to provide means for effectively supporting a stack of caps and for isolating the lowermost cap and supporting the remainder of the stack while the said lowermost cap is ejected.

The invention is particularly applicable to a milk bottle capping machine such as is disclosed in Patent No. 1,956,218, granted April 24, 1934, to G. J. Huntley and Harry A. Rau, although not limited to such association. According to the said patent a stack of caps is supported at three localized points and consequently deformation of the lowermost cap is apt to occur as a result of the superimposed weight, especially if the cap metal is light. According to the present invention the lowermost cap rests on ample supporting surfaces and prior to each ejecting operation caps above the lowermost are somewhat upwardly displaced so as to free the latter sufficiently for lateral movement. This operation is effected, according to the preferred embodiment of the invention which will be hereinafter described in detail, by a single movable blade and consequently, as over the device of the above mentioned patent, wherein there are several movable supporting members for the stack, the cost of manufacture is materially lowered.

Another substantial advantage is that according to the present invention there is positive separation of the caps if stuck together by lacquer or sealing compound, and very thin discs can be separated without distortion. According to the said patent the lowermost disc is separated from the remainder and drops freely to position for ejection. According to the preferred embodiment of the present invention, however, a portion of the weight of the remainder of the stack rests on the separated lowermost cap so that the latter is held down and is bound to be engaged by the ejecting member.

Moreover, in a capping machine including our improved feed mechanism, there is no wastage when the head becomes jammed, as no caps will be separated from the stack except the one which is being applied to the bottle. Since the present mechanism permits the use of caps of lighter material, the cost of the cap is reduced and in the capping of bottles therewith there will be less breakage than heretofore due to the smaller sealing pressure required.

Reference will now be made to the illustrative embodiment of the invention shown in the accompanying drawings in which:

Figure 1 is a side elevation of capping appa-

ratus including the cap feeding mechanism of the present invention.

Figure 2 is a section substantially on line 2—2 of Figure 1.

5 Figure 3 is a vertical section of the lower portion of the apparatus of Figure 1 taken substantially on the line 3—3 of Figure 2.

Figure 4 is a section substantially on line 4—4 of Figure 2 with the parts occupying the position 10 shown in the latter figure.

Figure 5 is a section like that of Figure 4 but showing the parts in a different relation.

Figure 6 is a plan view of a form of cap which the disclosed apparatus is particularly designed 15 to feed, and

Figure 7 is a diametrical section of the cap of Figure 6.

Referring to the drawings, reference numeral 10 designates a vertical cylinder adapted to be 20 fixedly secured to any suitable support as by bolting through a flange 11. Reference numeral 12 designates the shank portion of a capping head 13, the said shank portion being splined in the cylinder 10 for limited vertical reciprocation and 25 normally occupying its lowermost position. A vertical tube 14 fixed on the head casting constitutes with the vertically bored underlying portion 15 of the latter a cap magazine M. Pivoted to portion 15 at 15' is a base block 16 which is 30 adapted to be held in the full line operative position of Figure 1 by latch means 17, the block being adapted to swing to the dotted line position to give access to the capping head.

Block 16 is provided with a vertical cylindrical 35 throat 18 which, in the latched position of the block, is coaxial with a presser foot 19 and with an expandable sealing ring 20 which normally lie above a cap supporting flange 21 formed in the upper portion of the throat. With a cap, such as 40 is shown in Figures 6 and 7, supported on flange 21, a bottle elevated into the throat 18 will move the cap upwardly against the presser foot 19 and the cap will be applied in the manner fully disclosed in the Huntley et al. patent and needing no 45 repetition here since the present development is concerned solely with mechanism for feeding caps from a stack, as in the magazine M, to a position such as on the flange 21.

Fixed to the bottom of portion 15 in opposite 50 recesses are plates 22 and 23 whose margins project within the cylindrical bore of the magazine and are arcuately recessed as particularly shown in Figure 2. These inwardly projecting margins of plates 22 and 23 serve to support a stack of caps C in the magazine, opposite por-

tions of substantial area of the lowermost cap resting on these margins without danger of distortion due to the superimposed weight. Adjacent the capping head the wall of portion 15 is recessed at its lower end, as at 14', Figure 3, above the top level of plates 22 and 23 to provide clearance for the movement of a cap on the latter toward the capping head and the wall of throat 18 adjacent the magazine is recessed at 18' just above flange 21 to provide similar clearance and to provide continuations of the top surfaces of plates 22 and 23 flush with the top of the flange. By means which will now be described, a cap can be propelled from the magazine along the rails constituted by plates 22 and 23 into the throat 18 for application to a bottle.

Beneath portion 15 the block 16 is provided with a horizontal cylindrical bore 24 interrupted at the top by a parallel walled slot 25. Guided in bore 24 is a cylindrical member 26 to the top of which is secured a longitudinally extending bar 27 which is guided by the edges of slot 25. The top surface of bar 27 is flush with the top surfaces of plates 22 and 23, or is below the latter, except at its forward end where it is provided with an upward projection 28, the said forward end projecting somewhat beyond member 26. Horizontally elongated slots 29 and 30, Figures 1 and 3, are formed in the side walls of the bore 24 and through these project coaxial trunnions 31 and 32 which are secured to slide member 26. A bell crank lever 33 is pivoted intermediate its arms 34 and 35 on a pin 36 mounted in a horizontal bore of the fixed member 10. The arm 34 is pivoted at 37 to the tube 14 and the lower end of arm 35 is pivoted at 38 to one end of a link 39 whose other end pivotally engages trunnion 31. On the opposite side of the machine another bell crank lever exactly like lever 34 is pivoted on pin 36 and at the end of its short arm to tube 14 coaxially with the pivot point 37, the long arm 40, Figure 2, of this second lever being pivotally connected with trunnion 32 through a link 41.

In Figures 1 to 4, the head is in its lower position relative to the casing 10 and from Figures 2 and 3 it will be seen that the projection 28 of slide member 27 is directly adjacent the outer periphery of flange 21, suitable clearances being provided for the leading end of the slide member beneath the path of the cap. During the capping operation the bottle lifts the head causing the levers as at 34 to swing in a clockwise direction about pivot 36 so that slide member 27 is moved to a position wherein the projection 28 lies just to the left of the bore of the magazine, Figures 2 and 3. When the bottle is lowered at the end of the capping operation, the head follows downwardly, reversely swinging the levers as at 34 so that the slide member 27 is returned to the position of Figures 2 and 3.

As here shown, each cap C has a flat marginal portion C¹ and a circular upwardly offset portion C². Complete nesting of the caps is preferably prevented by protuberances as at C³, such provisions being disclosed in Reissue Patent 19,422, issued to G. W. Booth, January 13, 1935. The marginal portion C¹ of the cap is of uniform thickness and adapted to rest flatly on the inner margins of plates 22 and 23.

Pivoted above plate 23 on a vertical axis at 42 in a recess in the superjacent side wall of the portion 15 is a blade 43 having an angular horizontal edge 44 presenting a point 45. Above the

edge 44 is an inclined or wedge surface 46 which terminates in a flat top surface 47 of the blade. The lower leading portion of the blade has a horizontal undercut 48 so that edge 44 is spaced above the surface of plate 23 a distance slightly greater than the thickness of the cap margin C¹.

Fixed to lever 35 is a plate 49 whose inner face is recessed to provide a cam 50, Figure 2, having a face sloped to the right away from a plane surface or dwell 51, the latter terminating in a laterally elongated hook formation 52. Blade 43 has fixed therein an upwardly projecting pin 53 cooperable with the cam and hook in a manner which will now be described.

In Figures 2, 3 and 4 the head is assumed to be in the down position of Figure 1 and it is assumed that a cap C is supported on the flange 21 of throat 18. The stack in the magazine is supported on plates 22 and 23 and possibly, although not necessarily, on the flat top surface of the slide member or ejector 27. Blade 43 is entirely outside of the magazine bore and hence free of the caps in the latter. Pin 53 is in the hook 52 of plate 49.

As a bottle is now elevated into the throat 18, the head is carried upwardly and the levers as at 34 are swung in a clockwise direction as herefore mentioned. Projection 28 strikes the lowermost cap during the enforced return motion of the slide and agitates and loosens the stack. The flat surface 51 of plate 49 has been moving along pin 53 without affecting the latter, but as the slide approaches its left hand limit position, cam 50 reaches the pin with the result that blade 43 is swung in a clockwise direction and the edge 44 is forced between the lowermost cap, without affecting the latter, and the succeeding cap. The edge of the succeeding cap is engaged by the wedge surface 46 and rides up thereon a distance determined by the thickness of the blade so that the upward offsets of the lowermost cap and succeeding cap are substantially unnested, Figure 5. The effective thickness of the blade may, of course, be varied in accordance with the height of the offsets.

The weight of the stack is now supported partly on top of blade 43 and partly on the opposite margin of the lowermost cap. The blade closely overlies, without bearing on, the marginal portion of the lowermost cap which is in the cutout 48 and consequently it is impossible for the said lowermost cap to escape from square support on rails 22 and 23. The amount of inward projection of the edge 44 is, of course, determined by the height of cam 50, and the latter is chosen so that the said edge will stop short of the offset of the lowermost cap.

As the head and magazine lower at the end of the capping operation, plate 49 is swung in a counter-clockwise direction and cam 50 releases pin 53. Projection 28 of the ejector strikes the bottom cap and carries the latter from beneath the remainder of the stack to the ledge 21. As this position is approached the hook 52 strikes pin 53 and the blade 43 is returned to the position of Figures 2 and 4 and the machine is ready for the next capping operation.

It will be understood that the disclosure herein is intended as typical and not as restrictive of the invention and that we do not limit ourselves to details of construction except as in the following claim.

We claim:

Cam feeding apparatus comprising means providing a bottom support for a stack of caps, a

reciprocable blade at one side of said stack and movable between a position outside of the stack to a laterally inserted position in the stack just above the lowermost cap in a manner to displace upwardly and support caps above said lowermost cap, a vertically extending pin on said blade, a member reciprocable adjacent said blade, said member including a cam effective in one direc-

tion of movement of said member to insert said blade and including an abutment portion engaging said pin in the other direction of movement of said member to retract said blade, and means for ejecting said lowermost cap while the blade is inserted.
